UNITED STATES PATENT OFFICE

HERBERT J. KRATZER, OF ST. LOUIS, MISSOURI

TWO-CYCLE MOTOR

Application filed November 23, 1927. Serial No. 235,203.

This invention relates to improvements in a two-cycle internal combustion motor having for its primary object the purpose of providing improved means whereby a maximum fuel efficiency will be obtained with the simplest and most reliable mechanical means.

A further object of the invention is to provide a motor with means which will entirely change the true operative cycle as compared to either of the four-cycle or two-cycle principle now in use.

A further object of the invention is in providing the motor with means whereby in the cycle of operation the expansion or working stroke is longer than the compression stroke.

Another further object of the invention is in providing the motor with improved means whereby the exhaust port is closed before the inlet port is closed.

Still another object of the invention is in providing a two-cycle internal combustion motor of a construction whereby the power cycle operation of the motor is given an expansion ratio which exceeds the compression ratio.

Another still further object of the invention is to provide a two-cycle motor with improved means for introducing the fuel charges into the cylinders in a different manner.

Other and further objects will appear in the specification and be specifically pointed out in the appended claims, reference being had in the accompanying drawings, exemplifying the invention, and in which:

Figure 1 is a vertical section taken through this improved motor on the approximate line indicated at I—I in Fig. 2.

Figure 2 is a horizontal section taken approximately on the line II—II of Fig. 1.

Figure 3 is a schematic diagram indicating approximate time and duration of cyclic piston operations of expansion, exhaust, in-

take and compression portions of piston stroke.

Referring by numerals to the accompanying drawings, 1 designates the cylinder of this improved two-cycle motor having the cylinder head 3 and depending from the cylinder is the upper portion 4 of the crank housing 5 and secured to the housing is the pan 6.

Horizontally disposed and supported within the housing 5 is a crankshaft 6 having a crank 7 and secured to said crank is a connecting rod 8, said rod being secured at its upper end to the wrist pin 9 of a piston 10. Mounted in the cylinder 1 is a sleeve 11, said sleeve bearing against the cylinder wall and the piston 10 being mounted within the sleeve.

Abutting against the cylinder 1 on one side is an intake manifold 12 and leading upwardly from said manifold to the cylinder 1 is an intake port 13 and for communication with said port is an upwardly and inwardly inclining opening 14 which is formed in the sleeve 11. Located in abutting relation with the opposite side of the cylinder 1 is an exhaust manifold 15 and formed in the cylinder wall is a port 16 which forms communication between the cylinder 1 and the exhaust manifold 15 and for operative communication with said port 16 is an opening 17 which is formed in the sleeve 11.

Formed on the crankshaft 6 is a cam 18 and mounted over said cam is an eccentric 19 and extending upwardly from said eccentric is an extension 20 and pivotally secured at 21 to said extension 20 is a leg 22 which is depended from the sleeve 11.

For the purpose of illustration only one cylinder of this improved two-cycle motor is shown although in practise the motor will comprise several cylinders and operable parts therefor and it is my intention to provide a gaseous pressure by means removed from the crankcase of the motor and to maintain a pressure in the intake manifold 12 as shown

and illustrated in my pending application, Serial No. 164,898, filed January 31, 1927, this application showing a tubular controlling member 23 mounted in the intake manifold 12 and having an opening 24 formed therein for communication with the port 13.

In the operation of this improved motor, when a gaseous pressure is maintained within the controlling member 23 which is located inside of the intake manifold 12, and the motor is in operation in which the crankshaft 6 will be rotated in the direction of the arrow 25 in Fig. 1 in which the piston 10 is being travelled downwardly by force of the explosion created in the chamber 26 which is provided by the sleeve 11, the openings 14 and 17 of the sleeve 11 will be in positions upwardly disposed above respective ports 13 and 16. As the piston travels during the first 80 degrees of crank rotation with increasing velocity the sleeve 11 travels upwardly with decreasing velocity due to the actuating eccentric 19 being located approximately 80 degrees behind the crank throw. As the piston continues to travel downwardly on the power cycle operation the crank rotation will be approximately 145 degrees of travel from where the power cycle commenced before the sleeve 11 has started on its downward stroke and thereby the exhaust opening 17 will begin to communicate with the exhaust port 16 of the exhaust manifold 15. Assuming constant angular velocity of crankshaft, it can be seen during the next and last 35 degrees of crank rotation necessary to complete the downward stroke of the piston, the piston will travel at decreasing speed the remaining approximate six per cent of its stroke at a speed relatively slow to a total stop at 180 degrees. As the eccentric 19 which operates the sleeve 11 is delayed or located 80 degrees behind the crank throw, said eccentric will approach and pass its highest speed of travel during the time of the shortest angular travel of the crank shaft.

After the piston has reached the end of its power cycle stroke after 180 degrees of crank throw and the piston is being travelled upwardly on its compression stroke or cycle, it is obvious therefore that the exhaust opening 17 of the sleeve is in approximate full register with the exhaust port 16, this occurring when the crank throw is approximately 80 degrees past the dead center, and as said piston is now travelling upwardly and with increasing velocity compared to the constant angular velocity of the crankshaft, the piston begins to pass the exhaust opening 17 which is in register or alignment with the exhaust port 16, therefore the closing operation of the exhaust opening 17 is even more prompt than the opening operation with respect to the opening 17 communicating with the exhaust port 16.

At about the time the piston reached the

end of its downward stroke, the downward travel of the sleeve 11 caused the intake opening 14 to commence communication with the inlet port 13 and by reason of the upward inclination of opening 14 as well as the tangential disposition of said opening and the port 4, the gaseous fuel will be directed upwardly in the cylinder as well as spirally as indicated by the arrows 27 in Figs. 1 and 3 as the wall of the cylinder will cause the fuel to swirl as it travels upwardly, said upward swirling of the fuel forcing the burnt gases in the cylinder core downwardly where they will be discharged through the exhaust opening 17 and exhaust port 16, this occurring before the opening 17 is closed by the piston. As the opening 17 is being closed by the upward travel of the piston, the inlet opening 14 has just travelled to full opening register with the inlet port 13 and immediately after the exhaust opening 17 has been closed the piston will begin to close the inlet opening 14, said opening 14 however not being entirely closed until after the exhaust opening 17 has been sealed or closed by the piston. Immediately upon the closing of the inlet opening 14 the compression operation of the piston begins and is continued until the piston reaches the end of its upward stroke and immediately thereafter the piston is forced downwardly on its power stroke or cycle and before the piston on its downward travel passes respective openings 14 and 17 in the sleeve 11, the said openings are out of register with respective inlet and outlet ports 13 and 16, said ports then being sealed by the sleeve body.

Briefly summarized, the intake opening 14 starts to register with intake port 13 to admit fuel to the cylinder when the crankshaft is at lower dead center, the size of intake opening increasing at a decreasing rate of speed until wide open at the time the crank is 80 degrees past lower dead center, the inlet opening 14 then being rapidly closed during the following 10 degrees of crank rotation by piston travelling at increasing velocity. During the time the crank revolved through approximately 90 degrees starting from lower dead center, the piston actuated by the crank and connecting rod in this distance of its travel is truly an exhaust stroke as the piston during the greater portion of this part of the upward stroke displaces the spent gases below the exhaust port level out through the exhaust together with the spent gases being displaced from the upper end of the cylinder by the upwardly directed tangential stream of new fuel charge.

A roller 28 is mounted on the pin 21 for operative engagement with the guideway 29 in the housing 5.

With reference to Fig. 3 which is intended to show the cyclic operations accomplished by the piston, the curve portion starting 130

from A and extending to B representing the travel of crank wrist pin during expansion or working stroke of piston. Curve from B to C indicates approximate timing and duration of crank pin travel during which time exhaust port is open followed by curve C D representing crank pin position during compression stroke. Curve E F represents the approximate timing and duration of crank travel during which time intake port is open as indicated at E F and occurs simultaneously with lower part of curve B C and first portion of C D thus graphically showing intake port remaining open after exhaust port is closed with compression as indicated starting before intake ports are actually closed. This feature of intake closing after exhaust port closes, coupled with the fact that pressure in intake manifold is the primary cause of displacing the spent gases in cylinder through exhaust port constitutes the desirable operating characteristic of inherently producing higher compression pressure with increase of engine speed. The portion of travel from C to F on curve which represents the time intake valve remains open after exhaust port closes at the beginning of the compression portion of stroke is included in the compression stroke by virtue of the increased pressure in the intake manifold producing a pressure in cylinder above piston at time crank arrives at point F which pressure would be greater than had piston moved due to crank travel from curve C to F with all ports closed.

Obviously, but one specific showing of the invention is disclosed in which the sleeve travel is delayed behind the piston travel and the downward travel of said sleeve controls the instant of opening both inlet and exhaust ports; the piston travel on upward strokes determining the instant of closing respective ports. However, it is anticipated that the ports can be located in different positions with respect to other eccentric positions relative to the crank, one of which other positions of eccentric location in respect to crank throw being approximately 90 degrees in advance in which the sleeve travel upwardly would determine the instant of opening of exhaust and inlet ports and also the closing of inlet port and the piston on its upward stroke determining the instant of closing the exhaust port only. With this in view it is clear that other modifications than that shown can be made within the scope of the invention.

What I claim is:

1. A two-cycle motor having a cylinder, an inlet port and an outlet port, a sleeve having openings therein which are cooperable with respective ports, a piston reciprocal within said sleeve being cooperable with the openings of said sleeve for closing them on its outward stroke, a crankshaft, and a connecting

rod for said sleeve and said piston operable from said shaft.

2. A two-cycle motor having a cylinder, an exhaust port and an inlet port for said cylinder, a sleeve cooperable with said ports, a piston mounted in said sleeve, means provided in the sleeve whereby the exhaust port is closed before the inlet port is closed by the piston, a connecting rod for said sleeve and said piston, and a crank shaft to which said connecting rods are directly connected. 75

3. A two-cycle motor having a cylinder, an inlet port and an exhaust port for said cylinder, a sleeve cooperable with said ports, and a propelling piston cooperable with said ports, said ports being disposed a distance away from the piston when the piston is at the end of its working stroke. 80

4. A two-cycle motor having a cylinder, an inlet port and an exhaust port for said cylinder, a sleeve cooperable with said ports, a propelling piston reciprocal in said sleeve, said ports being disposed in the cylinder intermediate of the working length of the cylinder, and a crank shaft with which said sleeve and said piston are cooperably connected. 85

5. A two-cycle motor having a cylinder, an inlet and an exhaust port in said cylinder, a reciprocating sleeve cooperable with said ports when said sleeve is inwardly travelled, a piston cooperable with said ports when said piston is outwardly travelled, and a crank shaft with which said sleeve and said piston are cooperably connected. 95

6. A two-cycle motor having a cylinder, an inlet port and an outlet port, a sleeve having openings therein which are cooperable with respective ports when said sleeve is inwardly travelled, a piston cooperable with said openings of said sleeve when said piston is outwardly travelled, and a crankshaft with which said sleeve and said piston are cooperably connected. 105

7. A two-cycle motor having a cylinder, an upwardly inclining inlet port in communication with said cylinder, said port being directed in said cylinder tangentially thereto, and an exhaust port leading from said cylinder on a plane below said inlet port and above the piston when the piston is at the end of its working stroke. 110

8. A two-cycle motor having a cylinder, an exhaust port, an inlet port disposed on a plane above the exhaust port, a sleeve cooperable with said ports, and a single piston in said sleeve, said piston and said sleeve providing means whereby the piston closes the inlet port after the exhaust port. 120

9. A two-cycle motor having a cylinder, an inlet port and an exhaust port for said cylinder, said inlet port being disposed on a plane above the exhaust port, a sleeve cooperable with said ports, and a piston, said ports being disposed a distance away from the piston 125 130

when the piston is at the end of its working stroke, and a crank shaft to which said sleeve and said piston are cooperably connected.

10. A two-cycle motor having a cylinder, 5 an inlet port and an exhaust port for said cylinder, said inlet port being disposed on a plane above the exhaust port, a sleeve co-operable with said ports, and a piston reciprocal in said sleeve, said ports being disposed 10 in the cylinder remote from the cylinder head thereof and from the piston when the piston is at the end of its working stroke.

11. A two-cycle motor having a cylinder, an inlet port and an exhaust port for said 15 cylinder disposed intermediate of the length thereof, said inlet port being disposed on a plane above the exhaust port, a sleeve in said cylinder having ports for cooperation with said cylinder ports, a piston in said sleeve, 20 said ports of said sleeve being disposed a distance away from the piston when the piston is at the end of its working stroke.

12. A two-cycle motor having a cylinder, an intake manifold, an inlet port forming 25 means of communication from said manifold to said cylinder, means for maintaining a pressure above atmospheric on the gaseous fuel contained in said manifold, an exhaust port, a reciprocating sleeve co-operable with 30 said inlet port and said exhaust port when said sleeve is inwardly travelled, a piston co-operable with both of said ports when said piston is outwardly travelled, a crankshaft, and operating means for said sleeve and said 35 piston directly connected to said shaft.

13. A two-cycle motor having a ported cylinder, a ported sleeve in said cylinder, a piston in said sleeve, means for reciprocating said sleeve and said piston, the ports of said 40 sleeve being disposed in positions in said sleeve whereby the approximate length of the inward stroke of the piston will be an expanding power stroke, and the said ports of said sleeve being adapted to communicate 45 with the ports of the cylinder during the outward stroke of the piston in a manner wherein the first part of the outward stroke of the piston will provide for the exhausting and refueling operations of the cylinder, and 50 the latter part of the outward stroke of the piston will be a compression stroke.

14. A two-cycle motor having a ported cylinder, a ported sleeve in said cylinder, a piston in said sleeve, means for reciprocating 55 said sleeve and said piston, the ports of said sleeve being disposed in positions in said sleeve whereby the approximate length of the inward stroke of the piston will be an expanding power stroke while the cylinder 60 ports are closed, and the said ports of said sleeve being adapted to communicate with the ports of the cylinder during the outward stroke of the piston in a manner wherein the first part of the outward stroke of the piston will provide for the exhausting and refueling 65

operations of the cylinder, and the latter part of the outward stroke of the piston will be a compression stroke during when all of said ports are closed.

15. A two-cycle motor having a ported cylinder, a ported sleeve in said cylinder, a piston in said sleeve, means for reciprocating said sleeve and said piston, the ports of said sleeve being disposed in positions in said sleeve whereby the approximate length of the inward stroke of the piston will be an expanding power stroke while the cylinder ports are closed, and the said ports of said sleeve being adapted to communicate with the ports of the cylinder during the outward stroke of the piston in a manner wherein the first part of the outward stroke of the piston will provide for the exhausting and refueling operation of the cylinder, and the latter part of the outward stroke of the piston will be a compression stroke during when all of said ports are closed by the piston. 70 75 80 85

16. A two-cycle motor having a ported cylinder, a sleeve in said cylinder having an inlet port and an exhaust port formed in the wall thereof intermediate of the length of the sleeve, the inlet port of said sleeve being disposed on a plane above the exhaust port, a piston in said sleeve, means for reciprocating said sleeve and said piston, said ports of said sleeve adapted to intermittently communicate with respective ports of said cylinder when said sleeve is reciprocated, said ports of said sleeve being out of communication with the ports of the cylinder during the approximate length of inward travel of the piston and adapted to communicate with the cylinder ports during the approximate first part of the outward travel of the piston. 90 95 100

17. An internal combustion motor having a cylinder, an upwardly inclined inlet port in communication with said cylinder, said port being directed in said cylinder tangentially thereto, an exhaust port leading from said cylinder on a plane inwardly of said inlet port and above the piston when the piston is at the end of its working stroke, and a sleeve co-operable with said ports. 105 110

18. An internal combustion motor having a cylinder, an upwardly inclining inlet port adapted to communicate with said cylinder, a sleeve in said cylinder having an opening therein for communication with said inlet port, said inlet port and said opening of said sleeve being directed in said cylinder tangentially thereto, and an exhaust port leading from said cylinder on a plane below said inlet port and above the piston when the piston is at the end of its working stroke, said sleeve having an opening therein for cooperation with said exhaust port. 115 120 125

19. An internal combustion motor having a ported cylinder, a ported sleeve in said cylinder, a piston in said sleeve, means for reciprocating said sleeve and said piston, the 130

ports of said sleeve being adapted to communicate with the ports of the cylinder during the outward stroke of the piston in a manner wherein the first part of the outward stroke of the piston will provide for the exhausting and refueling operations of the cylinder, and the latter part of the outward stroke of the piston will be a compression stroke which is shorter in length than the approximate length of the expansion stroke of the piston.
